UNITED STATES PATENT OFFICE

PAUL POPOVICH, OF MONTREAL, QUEBEC, CANADA

SHOE-SHINING DEVICE

Application filed October 25, 1929. Serial No. 402,482.

This invention relates to improvements in shoe polishing brushes.

The primary object of this invention, is to provide a device of the above mentioned character having a reservoir carried by the handle for supplying a charge of polish to the shoe to be polished by means of a force feed.

A further object of this invention is to provide a device of the above mentioned character having a removable reservoir carried by the handle of the brush which may be removed for the purpose of filling.

A still further object of this invention, is to provide a polish reservoir in the handle of a brush having communication with the bristles at one end of the brush for supplying polish thereto.

A still further object of this invention is to provide a polish reservoir for a shoe brush having a collapsible upper portion adapted to be operated or collapsed by a plunger mounted on a pivoted finger operated lever associated with the brush handle.

Other objects and advantages of the invention will become apparent during the course of the following description forming a part of this specification.

In the drawings Figure 1 illustrates a top plan view of the shoe polishing brush showing the reservoir housing and the brush hand hold.

Figure 2 is a side elevational view of the invention showing the hinged reservoir casing and the peculiar configuration of the hand hold.

Figure 3 is a transverse sectional view taken on lines 3—3 of Figure 2 further illustrating the shape of the hand hold of the brush base.

Figure 4 is a longitudinal sectional view taken on lines 4—4 of Figure 1 illustrating the arrangement of the collapsible reservoir in the reservoir casing relative to the polishing brush.

Figure 5 is a vertical transverse sectional view taken on lines 5—5 of Figure 2 illustrating the manner of fastening the hinged reservoir casing to the brush base and showing the collapsible operating finger lever in its inoperative position.

Figure 6 is a horizontal sectional view taken on lines 6—6 of Figure 2 showing the construction of the interior bottom portion of the reservoir and its position relative to the brush base, and Figure 7 is a bottom plan view of the collapsible reservoir showing the same removed from the reservoir housing.

In the drawings wherein for the purpose of illustrating the invention and wherein like reference characters are employed to designate like parts throughout the same, attention is first directed to Figure 4 wherein is shown a base portion 10 having imbedded in the bottom wall thereof bristles 11 which are mounted in circular openings 12 in a well known manner.

At one end of the base portion 10 is a hand hold 13 having opposite grooves 14 on the sides thereof for accommodating the fingers of the user. At the opposite end of the base portion 10 is formed a housing 15 which extends above the level of the hand hold 13. An opening 16 is formed in the housing 15 and said opening has its bottom divided into three outlets 17 for accommodating the necks 18 of a polish reservoir 19. The polish reservoir 19 has its bottom divided into three throats as at 20 which terminate in the neck portions 18. Secured to each of the neck portions 18 is a rubber tube 21 having a fringed lower portion 26 which is shorter than the bristles of the brush 11. Secured about the rubber tube 21 adjacent the neck of the polish reservoir 18 is also a series of brush bristles 27 held in place by cord or the like designated at 28.

The polish reservoir 19 is provided with a flanged upper portion 29 adapted to be received in an enlarged portion 30 of the opening 16, whereby the downward movement of the polish reservoir 19 will be limited. A screw threaded ring 31 is threaded on the screw threads 32 on the upper portion of the polish reservoir 19 and secured to the screw threaded ring 31 is a rubber cap 33 in the form of a hemisphere. The rubber cap 33 may be secured to the ring 31 by a suitable adhesive or it may be fastened by a clamping ring 35.

Hingedly secured to the housing 15 is a

bulbous shaped casing 36 by means of a conventional form of hinge 37. Extending the vertical length of the bulbous shaped casing 36 is a slot 38 which terminates at its upper end in close relation to the top of the bulbous casing 36. Means is provided for holding the bulbous casing 36 in its closed position such as hooks 40 secured to staples 41 imbedded in the bottom portion of the bulbous casing 36 and on opposite sides of the slot 38. Staples 42 may be imbedded in the sides of the reservoir housing 15 for receiving the hooked ends of the hooks 40.

Hingedly secured to the upper part of the reservoir casing 15 is a lever 43 having one of its ends mounted in a bearing 44 and its opposite end extending through the vertical slot 38 of the bulbous casing 36 and terminating in a finger piece 45. The lever 43 is provided with a plunger 46 by means of the lever 43 passing therethrough and the plunger 46 has its lower portion spherically shaped as at 47 to engage and depress the rubber cap 33 of the polish reservoir 19, whereby polish therein will be fed through the rubber tube 21 to the bristles 27.

For consideration of the operation of the device the handle 13 is grasped and the bristles of the brush 11 are presented to the shoe of the user whereby the handle may be reciprocated for first brushing the shoe. After the shoe has been cleaned polish is applied by depressing the finger piece 45 of the lever 43 whereby polish in the reservoir 19 will be fed to the bristles at one end of the brush 10. After a sufficient supply of polish has been applied to the shoe the opposite end of the brush is then reciprocated over the shoe to give a finished lustre.

It is to be understood that the form of the invention herewith shown and described is to be taken as a preferred embodiment of the same and in the detailed description of the specification where is mentioned rubber parts, flexible parts of any material may be used with the same advantage. Changes in the shape, size and arrangement of the device may also be resorted to without departing from the spirit of the invention or the scope of the subjoined claims.

Having thus described my invention, what I claim is:—

1. A shoe polish applying brush comprising a brush, a handle formed at one end of the brush, a reservoir housing formed at the opposite end thereof, openings in the bottom of the reservoir housing communicating with the underside of the brush, a reservoir removably mounted in the reservoir housing, neck portions formed on the bottom of the reservoir having openings therein, flexible tubes secured to the neck portions of the reservoir, said neck portions and flexible tubes extending to the openings in the bottom of the reservoir housing, a flexible

cap secured to the removable reservoir and means associated with the reservoir housing for depressing the flexible cap.

2. In combination with a brush having bristles and a handle at one end, of a reservoir housing formed at the opposite end thereof, openings in the bottom of the reservoir housing communicating with the bristles at one end of the brush, a removable reservoir mounted in the reservoir housing, openings formed in the bottom wall of the reservoir communicating with the openings in the bottom of the reservoir housing, necks formed on the openings of the reservoir, flexible tubes secured to the necks of the reservoir, whereby fluid contained in the reservoir may be fed through the tubes to the bristles of the brush, a flexible cap for covering the reservoir, and a plunger adapted to be manually operated mounted above the flexible cap for depressing the same whereby fluid contained in reservoir will be forced through the openings therein and the flexible tubes.

3. In combination with a brush having a handle at one end, of a reservoir housing at the opposite end thereof, openings formed in the bottom of the reservoir housing communicating with the bristles at one end of the brush, a reservoir mounted in the reservoir housing, having open necks on the bottom thereof communicating with the openings in the bottom of the reservoir housing, flexible tubes connected to the necks of the reservoir extending through the openings in the reservoir housing, a flexible cap for the open end of the reservoir, means for depressing the flexible cap comprising a hinged lever secured to the reservoir housing, a plunger secured to the hinged lever, directly above the flexible cap, whereby reciprocation of the hinged lever will cause the flexible cap to be depressed and a hinged cover hingedly secured to the reservoir housing having a vertical slot for allowing the free passage of the free end of the hinged lever, whereby the lever may be reciprocated from the exterior of the hinged casing.

In testimony whereof I affix my signature.
PAUL POPOVICH.
